UNITED STATES PATENT OFFICE

90,910

DESIGN FOR AN EYEGLASS CASE OR SIMILAR ARTICLE

Harry J. Farrington, Jamaica Plain, Mass., as
signor to Farrington Manufacturing Company,
Boston, Mass., a corporation of Massachusetts

Application February 1, 1933. Serial No. 47,074

Term of patent 14 years

To all whom it may concern:

Be it known that I, HARRY J. FARRINGTON, a citizen of the United States of America, residing in Jamaica Plain, in the county of Suffolk and Commonwealth of Massachusetts, have invented a new, original, and ornamental Design for an Eyeglass Case or Similar Article, of which the following is a specification, reference being had to the accompanying drawing, forming a part thereof.

Fig. 1 is a top plan view of an eyeglass case showing my new design; and

Fig. 2 is a detailed section on the line 2—2 of Fig. 1.

I claim:

The ornamental design for an eyeglass case or similar article as shown.

Signed by me at Boston, in the county of Suffolk and Commonwealth of Massachusetts, this 26th day of January, 1933.

HARRY J. FARRINGTON.
